UNITED STATES PATENT OFFICE

JOSEF STARLING, OF ANGELHOLM, SWEDEN

PORTABLE CIRCULATION AND HEATING APPARATUS FOR TANNERIES

Application filed July 9, 1930, Serial No. 466,848, and in Germany July 18, 1929.

My present invention refers to a portable apparatus for tanning, heating and circulation of tanning liquors, and to a method of tanning, heating and circulation of tanning liquors.

In the rapid tanning by means of extracts, the hides in a manner previously known are subjected to a pre-tanning by suspending the same in a diluted tanning liquor, and the final tanning is performed by an intense treatment of the hides by means of a highly concentrated tanning liquor preferably in a rotating vat. This strenuous treatment of the hides, which is adhered to for the purpose of preparing the leather within a shorter period of time only, is injurious to the quality of the leather, and the leather will be of a superior quality when using the old and more time-wasting tanning methods, according to which the hides, at certain intervals of time, are successively transferred from vats containing weaker tanning liquors to others in which the liquors gradually increase in strength, or wherein the tanning liquor in the same vat, at certain intervals, is changed and is each time substituted by a stronger liquor.

In order to make this process a little less time-wasting it has, however, already been proposed to heat the tanning liquor in the vat and to keep it in circulation, but in such instances a specially built factory has hitherto been required, such factory being rather costly both in respect of erection and in the working.

By means of the portable apparatus according to the invention it will be possible, without a special and costly factory of the kind hinted at, in an advantageous manner to accelerate the tanning process by a suitable heating and circulation of the tanning liquor and by controlling the strength thereof without removing the hides or emptying the vat during the whole period of time spent in the tanning. The apparatus may also be found advantageous in use for de-hairing, or other treatment, of the hides, for instance a treatment with lime solution, or other solution, and for the purpose of heating and circulating such solution during the treatment.

An embodiment of the invention is illus-

trated in the accompanying drawings, wherein

Fig. 1 shows an elevation of the apparatus partly in longitudinal section, and

Fig. 2 shows a plan view of the same.

The apparatus consists of a tube 1, preferably produced from copper or aluminum, such tube being adapted to take a vertical position in the tanning vat at one of its corners, for instance so that the tube at its lower end rests directly on the bottom of the vat, as indicated in the drawings.

An electric motor 2 is mounted at the upper end of the tube 1, such motor preferably being supported by an adjustable bracket device. According to the embodiment shown this adjustable bracket means consists of rods 3 which by means of set screws are adjustably locked in eyes provided on a ring 4 at the upper end of the tube 1, and a ring 5 on the electric motor 2.

By means of an upper antifriction bearing 6 and a lower bearing 7 made from wood, for instance pock-wood, is mounted a shaft 8 centrally within the tube, such shaft being preferably made from brass and provided with a flexible clutch, for instance a rubber sleeve 9, at its upper end, such clutch forming a connection with the motor shaft 10, the lower end of the shaft being provided with a liquid propelling means 11.

At its lower end the tube 1 is provided with an inlet opening 12, the upper end being provided with an outlet socket 13, the axis of such means being preferably positioned at a right angle in relation to each other as will be seen in Fig. 1.

At the rotation, the propeller sucks in the tanning liquor through the opening 12 elevating the same within the interior of the tube and forcing it out through the outlet 13, and hereby an efficient circulation of the tanning liquor in the vat is performed. During its passage through the tube 1, the tanning liquor is subjected to a controllable heating by means of a heating element, mounted within the tube in a position so as to be passed in a heat transmitting relation by the liquor flowing therethrough.

In the embodiment shown, the said heating

element consists of a coil of copper piping 14, which at its upper end, by means of a control valve 15, by means of a hose 16 or the like is intended to be connected with a steam line, 5 preferably a line transmitting high pressure steam, or else a waste steam line may be used, the lower end of the said coil being connected with an outlet pipe 17 for water of condensation.

10 The control of the valve 15 is preferably performed automatically by means of a thermostatic controller subjected to the temperature of the heated fluid rising through the tube 1, and such controller may preferably 15 be mounted substantially at the outlet 13.

By means of this thermostatic controller, which can be constructed in any well-known manner and adapted to actuate the valve in a manner also known per se, the admittance 20 of the steam to the heating coil 14 is controlled in such a manner that the temperature of the liquor leaving the outlet 13 is kept substantially constant, and especially the temperature must not be permitted to raise 25 above a certain maximal limit even in case the motor should be brought out of working order for one reason or another.

The attendance needed is the smallest possible under the conditions described, but in 30 case the working or progress of the tanning is permanently attended to for other reasons, the control of the admittance of steam may naturally also be performed manually.

Instead of a steam coil, an electric heating element may be used, if the source of energy required is at hand at a cheap price. In any case it is advisable that the heating element is mounted within the tube 1, so that the upward flow of the liquid therein encircles the element, and further it is a condition that the liquid shall have a substantial rapidity of flow when passing the said element. Hereby the transmission of heat is increased and a periodical overheating of the element and deposition of solid particles on its heat transferring faces are prevented. It is to be noted that the tanning liquor is very sensitive to a too strong heating and will be injured thereby, and besides it always contains not only the dissolved ingredients but also suspended solids which when settling on the heat transferring faces will reduce the heating efficiency of the element and will be burnt by the same, so that the tanning liquor may be destroyed in a manner causing an injurious effect on the hides under treatment.

In the embodiment of apparatus shown in the drawings, the liquid rising within the tube 1 is given a rotating movement by means of the propeller; and hereby it is caused to take a helical path which is advantageous to the efficiency of the transfer of heat when passing the heating element. For the same purpose, and also for preventing the settling of solids 65 on the heating surfaces, serves a tubular cap-

per jacket 19 mounted around the propeller shaft 8 within the heating coil 14 and provided with a closed bottom end, this jacket being intended to confine the flow of the fluid into a comparatively narrow interspace between the outer tube 1 and the jacket 19 at the passage of the heating coil. Thereby an increased rapidity of flow is caused at this point and the liquid is carried intimately into contact with the heating coil.

The apparatus as a whole is so light that it may easily be carried and inserted in any vat desired, and it is so efficient in action that it, when combined with a motor of less than one horse-power (for instance one third horsepower only) and a heating surface amounting to 0,5-1,0 square metre, will be sufficient for performing a satisfactory heating and circulation of the liquor within a tanning vat having a volume of 30-50 cubic metres.

In order easily to perform an adjustment of the length of the apparatus according to different conditions, the lower end 1^a of the tube 1 is preferably constructed so as to be dismounted and substituted. In such case the same apparatus may be provided with a number of tube ends 1^a of different length and affixable according to requirements. The affixing of the substitutable tube end may thereby be performed for instance by means of rapid action coupling flanges 20 of a construction known per se.

The addition of tanning extract or chemicals for maintenance or changing of the composition of the tanning liquor, or the strength thereof, during the progress of the tanning process, may preferably be performed by means of the tube 1, and thereby the additions are rapidly distributed throughout the entire bulk of liquid within the vat. In this simple manner it will be possible, without costly arrangements, to perform the tanning in the common vat under utilisation of the advantages of the circulation and heating, without the necessity of removing the hides or the liquor, or both, from the vat, as has hitherto been the common practice.

Naturally, the invention is not limited to the particulars described above for the sake of explanation, and such particulars may be varied without departing from the principle.

What I claim and desire to secure by Letters Patent is:

1. In a portable circulation and heating apparatus for the purpose described, an upper tube section and a lower tube section separably connected with the former and adapted to be substituted by other lower tube sections of different length, an inlet provided substantially at the free bottom end of said lower tube section, an outlet provided substantially at the upper end of the upper tube section, propelling means for the liquid mounted in the combined tube, a prime mov-

er, mounted in connection with the upper tube section, transmission means between the said prime mover and the propelling means, and a heating element mounted in the combined tube so as to be passed in a heat transmitting relation by the liquid flowing from the inlet to the outlet thereof.

2. In a portable circulation and heating apparatus for the purpose described, a tube adapted to be positioned substantially vertically in a vat, an inlet provided substantially at the bottom end of such tube, an outlet provided substantially at the opposite end of the same, a prime mover, mounted at the upper portion of the tube, propelling means for the liquid mounted in the tube and adapted to be driven by the said prime mover and intended for causing a flow of liquid contained in the vat through said tube, a heating element mounted within the tube in a position so as to be passed by the liquid propelled therethrough, controlling means adapted for controlling the activity of the heating element, and a thermostatic controller mounted so as to be actuated by the liquid flowing through the tube and adapted to control the heating element in correspondence with the temperature of such liquid.

3. In a portable circulation and heating apparatus according to claim 2, the additional feature that the thermostatic controller is mounted substantially at the outlet of the tube so as to be sensitive to the temperature of the liquid which has passed the heating element.

4. In a portable circulation and heating apparatus according to claim 2, the additional feature that the tube is divided into two interseparable sections by means of a quick acting clutch, the prime mover and the propelling means being mounted on the upper section of the tube.

5. In a portable circulation and heating apparatus according to claim 2, the additional feature that the heating element is mounted in a comparatively narrow interspace between the tube wall and an interior tubular jacket therein such jacket having a closed bottom end and surrounds the transmission means between the prime mover and the propelling means.

6. In a portable circulation and heating apparatus according to claim 2, the additional feature that the heating element consists of a steam coil, the inlet of which is controlled by a valve means controlled by the thermostatic controller.

7. A portable apparatus for simultaneously heating and creating gentle circulation of a liquid contained in a large vat, which comprises an elongated tubular casing adapted to be positioned vertically in the vat preferably at a corner thereof and provided at its lower end with a liquid inlet and at its upper

end with a liquid outlet, a prime mover mounted on the top of the said tubular casing, a shaft journalled within the tubular casing and connected to the said prime mover to be rotated thereby, a propeller on the said shaft for forcing liquid through the said tubular casing from the inlet to the outlet thereof, and a heating device mounted within the tubular casing in spaced relation to the inner walls thereof between the liquid inlet and outlet of said casing for heating the liquid within the casing.

8. A portable apparatus for simultaneously heating and creating gentle circulation of a liquid contained in a large vat, which comprises an elongated tubular casing provided at its lower end with a lateral liquid inlet opening and at its upper end with a lateral liquid outlet opening and adapted to be positioned vertically in the vat preferably at a corner thereof with the said liquid outlet opening located immediately below the surface of the liquid in the vat, an electric motor mounted on the top of the said tubular casing, a shaft journalled within the tubular casing coaxially therewith and coupled to the said electric motor to be rotated thereby, a propeller on the lower end of said shaft for forcing liquid through the said tubular casing from the inlet to the outlet thereof, and a heating device arranged within the tubular casing in spaced relation to the inner walls thereof so as to be surrounded by the liquid within the casing for heating such liquid while it is flowing upwards from the inlet to the outlet of the casing.

9. A portable apparatus for simultaneously heating and creating gentle circulation of a liquid contained in a large vat, which comprises an elongated tubular casing provided at its lower end with a lateral liquid inlet opening and at its upper end with a lateral liquid outlet opening and adapted to be positioned vertically in the vat preferably at a corner thereof with the said inlet opening located near the bottom of the vat and with the said outlet opening located immediately below the surface of the liquid in the vat, the said lateral inlet and outlet openings being angularly offset in relation to each other, an electric motor mounted on the top of the said tubular casing, a shaft journalled coaxially in the said casing and connected to the said motor to be rotated thereby, a propeller on the lower end of said shaft for forcing liquid through the said tubular casing from the inlet to the outlet thereof, and a heating device arranged within the said tubular casing so as to be surrounded by the liquid in the said casing for heating such liquid while it is flowing upwards from the inlet to the outlet of the casing.

10. In a portable circulation and heating apparatus for the purpose described, a tube adapted to be positioned substantially verti-

cally in a vat, an inlet provided substantially at the bottom end of such tube, an outlet provided substantially at the opposite end of the same, a prime mover mounted at the upper portion of the tube, propelling means for the liquid mounted in the tube, a central shaft within the tube connecting the said prime mover with said propelling means, a coil shaped heating element mounted around the shaft within the tube in a position so as to be passed by the liquid flowing from the inlet to the outlet thereof, said heating coil being mounted in a comparatively narrow interspace between the wall of the tube and a tubular jacket surrounding said shaft, such tubular jacket being closed at its lower end.

In testimony whereof I have signed my name to this specification.
